H. H. WAMPLER,
BOTTLE CAPPING DEVICE,
APPLICATION FILED SEPT. 7, 1920.

1,369,205.

Patented Feb. 22, 1921.

INVENTOR
Homer H. Wampler,
BY
Howard A. Smith,
His ATTORNEY

UNITED STATES PATENT OFFICE.

HOMER H. WAMPLER, OF DAYTON, OHIO.

BOTTLE-CAPPING DEVICE.

1,369,205.

Specification of Letters Patent. Patented Feb. 22, 1921.

Application filed September 7, 1920. Serial No. 408,650.

To all whom it may concern:

Be it known that I, HOMER H. WAMPLER, a citizen of the United States, residing at Dayton, in the county of Montgomery and 5 State of Ohio, have invented certain new and useful Improvements in Bottle-Capping Devices, of which the following is a specification.

The principal object of my invention is to 10 provide a device or machine for capping bottles, that is simple and efficient in construction and inexpensive to manufacture. It is convenient, positive and powerful in 15 operation, and may be used equally well in the factory and the home for closing the mouths of bottles and jars.

It is another object of my invention to 20 provide an efficient and readily visible indicator for correctly adjusting the bottle capping mechanism to various sized bottles.

Other important and incidental objects will be brought out in the following specification and particularly pointed out in the subjoined claims.

25 In the accompanying drawings, Figure 1 is a side elevational view of my bottle capping device in the act of capping a bottle. Fig. 2 is a side elevational view of the upper portion of the capper, showing the cam in 30 its raised position. And Fig. 3 is a top plan view of my bottle capping device.

Throughout the specification and drawings, similar reference characters denote corresponding parts.

35 Referring to the accompanying drawings, the numeral 1 designates a base upon the front portion of which a bottle 2 is placed, and which terminates at its rear end in an upright tubular portion 3 which receives an 40 upright rod or standard 4 that is firmly held in the latter by a set screw 5. The base 1 is adapted to rest upon a table, stand or other supporting structure.

45 Vertically movable along the rod 4 is a slide 6. A vertical bore or hole in the rear portion of the slide receives the rod 4, to which it may be firmly secured in an adjusted position by means of a set screw 7.

The slide 6 has a pendant portion 8 that 50 projects over the top of the bottle. Vertically movable through a hole in the outer enlarged end of the pendant portion 8 of the slide 6, is a plunger 9 on the lower end of which is screwed a cap-applying head 10.

55 A coil spring 11 surrounds the plunger 9

between its head and the top of the pendant portion 8 of the slide 6, to exert pressure against the plunger head for the purpose of raising the cap-applying head 10 to its normal position against the bottom surface of 60 said pendant portion. (See Fig. 2.)

For the purpose of forcing the cap-applying head 10 down over the cap 12 of a bottle, to secure it firmly and properly thereon, the following means are provided. Preferably 65 secured by a bolt 13 to the outer end of the pendant portion 8, one on each side thereof, are the extreme front portions of two cam extensions 14, 14 of a lever 15 provided with a longitudinal groove 16 in its rear portion to receive the upper enlarged end of an operating rod 17 that is secured to said lever by a pivot pin 18. (See Figs. 1 and 3.) The ends of the cam extensions 14, 14 are 70 so formed that when the outer end of the lever 15 is pulled downwardly by the rod 17, they will press upon the top of the cap-applying head 10 of the plunger 9 to force it over the top 12 of the bottle. And as further pressure is applied to the outer end of the 75 lever 15, the outwardly bulged peripheries of the front ends of the cam extensions 14, 14 will press the cap firmly and evenly over the bottle mouth to thoroughly seal it. It is thus seen that the pressure which the cam 80 brings to bear upon the bottle cap is positive and powerful.

In order that the slide 6 may be set on the standard 4 at a point where the bottle capping mechanism just described, may 90 perform its function in the most efficient manner, there is formed on the bottom part of the slide an inwardly projecting reduced portion 19. Now when the latter is on a level with the top of the bottle, as shown 95 in Figs. 1 and 2, it indicates to the operator that the slide 6 should be set at that position on the standard 4 by tightening the set screw 7. This indicator thus reveals to the operator the position which the maker of 100 the device has found to be the proper one for the slide 6 during the bottle capping operation.

While the lever 15 may be operated by the hand to cap a bottle, it may also be conveniently actuated by a foot pedal 20 through the means now to be described. As shown in Fig. 1, the rod 17 projects downwardly through a hole in the supporting structure 21, terminating at its lower end in an eye 110

piece 22. Through a link chain 23, which may be removed for the substitution of one of a different size, the eye piece 22 is connected to a hook 24 secured to the foot pedal 20. The pressure of the foot upon the outer end of this pedal 20 will draw the lever 15 downwardly against the pressure of a coil spring 25 that surrounds the rod 17 between the supporting member 21 and a stop element 26 secured to the upper end of said rod. Therefore, when the pressure of the foot is released upon the pedal 20, the compressed spring 25, by virtue of the upward pressure which it exerts against the stop element 26, will return the lever and cam to their inoperative positions shown in Fig. 2, after the bottle has been capped.

Having described my invention, I claim:

1. In a device of the type described, the combination with a standard, of a vertically adjustable slide thereon, a vertically movable plunger in said slide, a cap-applying head on the lower end of said plunger, and a cam lever pivotally secured to said slide beyond the standard and plunger, adapted to engage said cap-applying head on the plunger to force a cap on a bottle.

2. In a device of the type described, the combination with a standard, of a vertically adjustable slide thereon, a vertically movable plunger in said slide, a cap-applying head on the lower end of said plunger, a cam lever pivotally secured to said slide beyond the standard and plunger, adapted to engage said cap-applying head for the purpose specified, and a spring surrounding said plunger between the top of said slide and the head of said plunger, to return the

latter to its normal position after being pressed down by the cam lever.

3. In a device of the type described, the combination with a standard, of a vertically adjustable slide thereon, means carried by said slide for forcing a cap on a bottle, and indicating means on the slide for registry with the top of the bottle for designating the proper position of said slide during the bottle capping operation.

4. In a device of the type described, the combination with a standard, of a vertically adjustable slide thereon, means carried by said slide for forcing a cap on a bottle, and an inwardly projecting lug on the slide for registry with the top of the bottle for indicating the proper position of said slide during the bottle capping operation.

5. In a device of the type described, the combination with a standard, of a vertically adjustable slide thereon, a pendant portion on said slide, that projects over a bottle, a plunger vertically movable through a hole in said pendant portion, a cap-applying head carried by the lower end of said plunger, a lever, a pair of forward cam extensions on said lever, and means located beyond the standard and plunger for pivotally securing said cam extensions to the pendant portion of said slide, one on each side thereof, to engage the cap-applying head on the plunger for the purpose specified.

In testimony whereof I have hereunto set my hand this 2nd day of September, 1920.

HOMER H. WAMPLER.

Witness:

HOWARD S. SMITH.
